UNITED STATES PATENT OFFICE.

JAMES B. HUDSON, OF CHARLOTTE, NORTH CAROLINA.

METHOD OF TRUING UP AND RENEWING LEATHER-COVERED ROLLS.

1,118,862.

Specification of Letters Patent. Patented Nov. 24, 1914.

Application filed March 4, 1914. Serial No. 822,460.

To all whom it may concern:

Be it known that I, JAMES B. HUDSON, a citizen of the United States, residing at Charlotte, in the county of Mecklenburg 5 and State of North Carolina, have invented new and useful Improvements in Methods of Truing Up and Renewing Leather-Covered Rolls, of which the following is a specification.

10 This invention relates to an improved method of truing up and renewing the leather covered rolls of cotton spinning or twisting machines, proposing a method which is especially applicable to the rolls 15 designated according to their sizes and to their relation in the machine as "slubbers," "intermediates," "speeders" and "spinning" rolls.

The object of the invention is to provide 20 a method by which rolls of the character stated, when badly worn, can be rapidly and inexpensively trued up and renewed. That is to say, the object of the method is two-fold; first, to restore the roll to a uniform cylindrical outline throughout its extent, and second, to renew the wearing surface of the roll whereby said surface shall have the same efficient properties in its action on the thread as that of the surface of 30 a new roll or of a roll newly covered.

Ordinarily, rolls of the character referred to, when badly worn, are re-covered; that is to say, the leather covering of the roll is wholly removed and an entirely new 35 covering is substituted. As the number of rolls used in the average cotton mill is relatively large and as the occasions for the renewal of the leather coverings of these rolls are relatively frequent, the expense involved in renewing the rolls by substituting a new leather cover is considerable and represents a relatively large item in the cost 40 of up-keep of any well regulated modern plant. The method proposed by the present invention substantially reduces the item of expense referred to, since it not only effects a great economy of time, but it is also substantially and intrinsically less expensive.

50 The accompanying drawings illustrate certain implements or appliances by which the various steps of the method may be conveniently and rapidly carried out.

55 In said drawings:—Figures 1, 2 and 3 are views showing appliances used in the

practice of the method and showing the manner in which the steps of the method are best performed.

Similar characters of reference designate 60 corresponding parts throughout the several views.

A selection having been made of those rolls which are in condition fit for renewal by the present method, the said rolls are first cleaned by brushes, brooms, or other 65 suitable means so as to remove from their surfaces all lint and other extraneous matter. The vital element of the process as applied to all rolls is what may be conveniently termed a "renewing solution." 70 All of the rolls to be restored, after having had their surfaces cleaned of lint, as above stated, are first treated with this renewing solution, which has the essential properties of penetrating or permeating the leather cov- 75 ering of the rolls, of softening the fibers of said covering, and of giving the badly worn or "dead" leather new life and resiliency. Any solution which has these properties to a sufficiently marked degree and which is 80 not otherwise detrimental to the leather, may be used in practising the method. It has been found, however, that the solution most satisfactory for this purpose, consists of like parts of water, wood alcohol, and 85 cotton-seed oil, with a small amount of gum tragacanth as a thickener, and a small amount of sodium sulfite, which both bleaches the solution and insures of its uniform consistency. A convenient method of 90 applying the renewing solution to the rolls is shown in Fig. 1 and consists in the use of a pad A of absorbent material, and of a mitt or glove B also of absorbent material. A suitable quantity of the renewing solu- 95 tion is poured upon the pad A and is allowed to soak into this pad or may be "worked" into the pad by means of a brush or other suitable implement. The worn roll is thereupon placed upon the pad and rolled 100 back and forth thereon, the operator working the roll back and forth with the mitt or glove B, which has its surface preferably composed of absorbent material and aids in distributing the solution uniformly over 105 the leather surface of the roll. The renewing solution, as above stated, thoroughly and very rapidly permeates the leather cov- ering of the roll. In fact, this solution per- 110meates the cover, sufficient for the purposes

of the invention, within a few seconds of time following its application.

The second step in the method, as applied to all rolls, is to subject them to simultaneous heat and pressure, preferably by ironing them on a metallic plate or table C. This plate is heated by any suitable means, conveniently, a gas stove, the degree of heat being determined by the skill and discretion

10 of the operator, the requirement being that it shall be sufficient to restore the roll to uniform cylindrical contour and to dry the renewing solution incorporated in the leather, but not sufficient to bake or injure the leather.

15 The roll is worked back and forth across the hot plate C by any suitable means, conveniently, a paddle D. By virtue of this step, the roll is "ironed out", so to speak, and its leather covering is restored to a uniform 20 cylindrical outline throughout its extent, and the renewing solution is heated and dried within said leather covering, so that its beneficial properties above explained are substantially aided.

25 The two steps above set forth, viz: first treating the roll with a renewing solution and then ironing the roll on a heated plate, are carried out in all cases. Where the specific means shown in the drawings is employed for effecting these steps, a few reciprocations of the rolls across the pad A or the hot plate C, as the case may be, is sufficient.

Following the second step, viz: ironing 35 the roll on the hot plate, it is necessary to discriminate in practising the remaining steps of the method between the more badly worn rolls on the one hand, usually the middle and back rolls, and the less badly worn 40 rolls on the other hand, usually the front rolls, and also to discriminate between rolls whose surfaces although deformed are relatively smooth, and rolls whose surfaces are not only deformed but are creased, scored, or scaled. It is convenient to first describe 45 the invention in connection with the more badly worn rolls, *e. g.*, the back or middle rolls, and it is assumed that these rolls have been subjected to the two steps of the 50 method above described, that is, that they have first been treated with the renewing solution and then ironed out on the hot plate. When the rolls are removed from the hot plate, they are substantially dry, but, as a 55 matter of precaution, it is preferred to allow them to remain idle for a few seconds, to insure that the drying of their leather coverings is complete.

The final step in the method, as applied to 60 worn middle or back rolls, is the treatment of these rolls with what may be conveniently termed a "toughening" solution. The properties of the solution are that it permeates the surface of the leather to a very slight 65 extent, and that it uniformly toughens the

fibers of the leather throughout the permeated zone. The toughening solution thus produces, in effect, a tenacious wear-resisting skin which is exceedingly efficient in resisting the wearing action of the threads which pass across the surface of the rolls. The invention is, of course, not restricted to any particular kind of toughening solution, and contemplates any solution which will furnish the results stated and will not be otherwise detrimental to the leather. It has been found, however, that the best results are obtained by the use of a solution composed of like parts of leather "extract" and wood alcohol. The leather "extract" is obtained by immersing leather scraps in a solution composed of caustic soda and water in the proportions, for example, of a pound of leather scraps, half a gallon of water, and a half pound of caustic soda. This mixture is allowed to stand for a half hour or more and is thereupon strained. The resulting product of course contains the soluble constituents of the leather, and when combined with wood alcohol and applied to the leather covering of the rolls, fills the softened and distended fibers or cells of the leather, attacking the leather uniformly and by virtue of its combination with wood alcohol drying very rapidly.

Any desired means may be employed for applying the toughening solution to the rolls. It is preferred, however, to employ means similar to that employed for the application of the renewing solution, such means consisting of an absorbent pad E and a glove or mitt F. The pad E is similar to but entirely distinct from the pad A above described, and the mitt or glove F is, in like manner, similar to but entirely distinct from the mitt or glove B above described.

The manner of applying the toughening solution is the same as that of applying the renewing solution. A suitable quantity of the solution is poured upon the pad E and is allowed to soak in or is worked in by the use of a suitable implement. The rolls, when dried, are reciprocated a few times across the pad E, the mitt F, which preferably also has an absorbent surface, being used for this purpose.

The rolls after their treatment with the toughening solution are allowed to stand until dry, and as above stated, dry very rapidly. When dry, they are preferably dusted 120 with talcum powder before being restored to the frames.

In connection with the renewal of the less badly worn rolls, *e. g.*, the front rolls, the method is varied following the second step, 125 *i. e.*, the ironing of the rolls upon the hot plate C. The front rolls are the power rolls, and it is therefore important that their surfaces should not only be regular, but should also have the property of frictionally en-

gaging the threads. In the treatment of the front rolls, it is neither necessary nor desirable to heat the plate C to the same degree as is required for the treatment of the back and middle rolls. This is for the reason that if the plate C is too highly heated, it is apt to harden the surface of the roll, and hence, to interfere with the necessary property of said surface of frictionally engaging the threads. The proper degree of heat of the plate C for the treatment of the front rolls can readily be determined by the operator. When the front rolls are merely worn, but their surfaces are relatively smooth, they are not treated with the toughening solution above described. Following the second step of the method, *i. e.*, the ironing of said rolls on the hot plate, they are a second time treated with the renewing solution, the pad A and mitt or glove B being used in the same manner as in the first instance. This second treatment with the renewing solution insures that the surface of the rolls shall have the property of frictionally engaging the threads, which property might not be present or at least sufficiently developed immediately upon the completion of the ironing operation. Following the second application of the renewing solution, the rolls are allowed to stand until dry, and when dry, are dusted with talcum powder and thereafter restored to their frames.

Front rolls which have their surfaces badly scaled are treated in the same way as front rolls which have smooth surfaces, except that an additional step of treating said scaled front rolls with the toughening solution is introduced between the ironing step and the step of making a second application of the renewing solution.

It has been conclusively determined by actual practice that rolls treated by the above method in the manner described are in substantially as good condition, both as regards their uniformity of outline and as regards the character of their wearing surfaces, as new rolls. By virtue of the method, the efficient life of a roll is greatly prolonged and the expense of overhauling the rolls in a cotton mill plant is greatly reduced, not only because of the great reduction in time required for overhauling the rolls, but also because of the elimination of the intrinsic expense of new leather covers.

In the preceding description reference has been made to the several steps of the method in connection with a single roll. It will be understood, however, that in actual practice a number of rolls, selected according to the choice and ability of the operator, are treated simultaneously; that is to say, a number of rolls are simultaneously reciprocated across the pads A and E as the case may be. The capacity of the invention for the simultaneous treatment of a number of

rolls is a further factor in the elimination of expense and delay in overhauling a relatively large plant.

Having fully described my invention, I claim:

1. A method of restoring worn leather covered cotton mill rolls which consists in treating the roll with a renewing solution having the properties of permeating the leather covering, of softening the fibers of said covering, and of giving the leather new life and resiliency and then subjecting the roll to simultaneous heat and pressure. 75

2. A method of restoring worn leather covered cotton mill rolls which consists in 80 treating the roll with a renewing solution having the properties of permeating the leather covering, of softening the fibers of said covering, and of giving the leather new life and resiliency and then "ironing" the 85 roll.

3. A method of restoring worn leather covered cotton mill rolls which consists in 90 treating the roll with a renewing solution having the properties of permeating the leather covering, of softening the fibers of said covering, and of giving the leather new life and resiliency, in then subjecting the roll to simultaneous heat and pressure, and in subsequently treating the roll with a 95 toughening solution.

4. A method of restoring worn leather covered cotton mill rolls which consists in 100 treating the roll with a renewing solution having the properties of permeating the leather covering, of softening the fibers of said covering, and of giving the leather new life and resiliency, in then ironing the roll, and in subsequently treating the roll with a 105 toughening solution.

5. A method of restoring worn leather covered cotton mill rolls which consists in 110 treating the roll with a renewing solution composed of wood alcohol, cotton-seed oil and gum tragacanth, and thereafter in subjecting the roll to simultaneous heat and pressure.

6. A method of restoring worn leather covered cotton mill rolls which consists in 115 treating the roll with a renewing solution composed of wood alcohol, cotton-seed oil and gum tragacanth, and thereafter in ironing the roll.

7. A method of restoring worn leather covered cotton mill rolls which consists in 120 treating the roll with a renewing solution composed of wood alcohol, cotton-seed oil and gum tragacanth, thereafter in subjecting the roll to simultaneous heat and pressure, and in subsequently treating the roll 125 with a toughening solution.

8. A method of restoring worn leather covered cotton mill rolls which consists in 130 treating the roll to restore it to true cylindrical outline and in the subsequent step of

treating the roll with a solution composed of wood alcohol and leather extract.

9. A method of restoring worn leather covered cotton mill rolls which consists in treating the roll to restore it to true cylindrical outline and in the subsequent step of treating the roll with a solution composed of wood alcohol and a mixture obtained by dissolving leather scraps in an alkaline 10 solution.

10. A method of restoring worn leather covered cotton mill rolls which consists in first treating the roll with a renewing solution having the properties of permeating the leather covering, of softening the fibers of said covering, and of giving the leather new life and resiliency, and in then subjecting the roll to simultaneous heat and pressure and in subsequently treating the roll 20 with a toughening solution composed of wood alcohol and a mixture obtained by dissolving leather scraps in an alkaline solution.

11. A method of restoring worn leather covered cotton mill rolls which combines the 25 steps of treating the roll with a renewing solution having the properties of permeating the leather covering, of softening the fibers of said covering, and of giving the leather new life and resiliency and of subjecting the roll to simultaneous heat and pressure.

12. A method of restoring worn leather covered cotton mill rolls which combines the steps of treating the roll with a renewing solution composed of wood alcohol, cot-

ton-seed oil and gum tragacanth, and of 35 subjecting the roll to simultaneous heat and pressure.

13. A method of restoring worn leather covered cotton mill rolls which consists in making a surface application to the roll of a renewing solution having the properties of 40 permeating the leather covering, of softening the fibers of said covering, and of giving the leather new life and resiliency and in subjecting the roll to simultaneous heat 45 and pressure.

14. A method of restoring worn leather covered cotton mill rolls which consists in making a surface application to the roll of a renewing solution having the properties of 50 permeating the leather covering, of softening the fibers of said covering, and of giving the leather new life and resiliency, in subjecting the roll to simultaneous heat and pressure, and in making a subsequent application 55 of a toughening solution.

15. A method of restoring leather covered cotton mill rolls which consists in treating the roll to restore it to true cylindrical outline, and in the subsequent step of treating 60 the roll with a toughening solution.

In testimony whereof I have hereunto set my hand in presence of two subscribing witnesses.
